UNITED STATES PATENT OFFICE.

JOHN M. DIEGEL, OF MINNEAPOLIS, MINNESOTA.

ELECTRICAL SIGNALING AND RECORDING SYSTEM.

Application filed December 6, 1920. Serial No. 428,700.

To all whom it may concern:

Be it known that I, JOHN M. DIEGEL, a citizen of the United States, residing at Minneapolis, in the county of Hennepin and 5 State of Minnesota, have invented certain new and useful Improvements in Electrical Signaling and Recording Systems, of which the following is a specification.

My invention relates to electrical signaling and recording systems. An object is 10 to provide a system which will operate signals and recorders when abnormal conditions arise in various devices, and which will also operate signals and recorders when the 15 devices are restored to normal conditions. Among the numerous devices and constructions with which my system may be employed are the following: automatic journal alarms, watchmen, automatic fire alarms, 20 manual fire alarms, fire doors, shutters, windows, grain storage bins, store doors, bank vaults, safes, bonded warehouses, water supplies in tanks and reservoirs, steam pressure, heating, temperature in cold storage rooms, temperature in greenhouses, 25 hospital calls, telephone calls, automobiles in garages, alarms for elevators and rope drives, and signals for grain elevators and flour mills.

30 My system will eliminate the personal equation present in any system involving personal inspections and report records. It will give constant supervision with an automatic and permanent record with audible 35 and visual notification to a central recorder and to one or more sub-recording stations, eliminating the necessity of checking reports and records which is always subject to oversight or neglect. The entire system 40 is preferably electrically operated from low voltage storage battery current.

An object in particular is to provide a system which will supervise automatic fire 45 sprinkler apparatus and hence my invention will be described more particularly in connection therewith. In such case the system consists of some or all of the following features: Electrical contacts or switches attached to all gate or stop valves under control of the assured, in feed pipes to sprinklers including all valves on tanks, fire pump, steam and discharge connections, pump suction, city main connections, post indicator valves, all tanks or their source of pressure, 50 55 pressure in dry and wet pipe systems, steam supply for fire pump, city water supply,

water level in all pressure tanks, surge tanks, gravity tanks, cisterns and reservoirs used as a supply for sprinkler service, temperature in all gravity tanks, cisterns and reservoirs used for sprinkler service in which water might freeze, and at the base of each 60 sprinkler riser all alarm valves to indicate the flow of water in the sprinkler systems. All of the above contacts or switches are 65 connected to a recording device and alarm boxes. All alarm boxes are connected to sub-recording stations located in the offices of as many executives as may desire notification. If so desired, alarm boxes may be 70 connected to any central station system or city fire department.

The operation in connection with gate valves is preferably as follows: Contacts on 75 all gate valves will give a signal between the first and second revolution of the hand wheel, tending to move the valve from its proper position, or when the valve is controlled otherwise than by a hand wheel, signal will be given before the valve has 80 moved one-fifth of the stem movement from its proper position. The particular valve disturbed is recorded automatically upon the central recorder by means of pens operated by electro-magnets upon a paper record 85 by embossing, puncturing or ink, also giving an audible signal by means of bell, gong, buzzer, horn or whistle, and a visual indication consisting of a red light warning signal. The signal is also sounded by 90 the operation of an alarm box connected to the central recorder to as many sub-recording stations as may be installed, or to any central station office or city fire department. The sub-recording stations consist of a single 95 stroke bell or gong, a punching or ink writing register and a prominent red light warning signal. When the valve is again restored to normal position a separate and distinctive signal is given, automatically recording upon the central recorder by means 100 of pens operated by electro-magnets upon a paper record by embossing, puncturing or ink. Also, an audible signal by means of bell, gong, buzzer, horn or whistle and red light warning signal is automatically eliminated. Also, an audible signal is, by means 105 of an alarm box connected with the central recorder, sounded to all sub-recording stations, and red light warning signals upon 110 sub-recorders or sub-recording stations are automatically eliminated. Red light warn-

ing signals upon the central recorder are automatically eliminated upon the restoration of any particular valve to normal position, but remain visible upon all sub-recording stations until all valves have been restored to their normal position.

The operation in connection with pressure is preferably as follows: All tanks and their sources of pressure, including steam supply for fire pumps, pressure in dry pipe and wet pipe systems, are provided with separate and independent contacts or switches. Pressure tank attachments will give a high and low signal at ten pounds below or thirty pounds above normal pressure but may be otherwise adjusted. Steam pressure attachments will give a low pressure signal at forty five pounds or otherwise according to adjustment. Attachments to dry pipe systems will give a high and low pressure signal at ten pounds variation above or below normal pressure or other variation depending on adjustments. Attachments to wet pipe systems will give a high and low pressure signal at twenty pounds variation above or below normal pressure or other variation according to adjustment. The variation of any particular pressure either above or below normal as hereinbefore outlined, is recorded automatically upon the central recorder by means of pens operated by electro-magnets upon a paper record by embossing, puncturing or ink, also, giving an audible signal by means of bell, gong, buzzer, horn or whistle, and a visual indication consisting of a red light warning signal. The signal is also sounded by the operation of an alarm box connected to the central recorder, to as many sub-recording stations as may be installed, or to any central station office or city fire department. When any particular pressure is again restored to normal, a separate and distinctive signal is given, automatically recording upon the central recorder by means of pens operated by electro-magnets upon a paper record by embossing, puncturing or ink. Also, an audible signal by means of bell, gong, buzzer, horn or whistle, and red light warning signal is automatically eliminated. Also, an audible signal is, by means of an alarm box connected with the central recorder, sounded to all sub-recording stations and red light warning signals upon sub-recording stations are automatically eliminated. Red light warning signals upon the central recorder are automatically eliminated upon the restoration of any particular pressure to normal, but remain visible upon all sub-recording stations until all pressure has been restored to normal.

The operation in connection with water levels is preferably as follows: When water drops twelve inches below the required level in any gravity tank, cistern or reservoir

or four inches below or rises four inches above the required level in any pressure tank the particular water level is recorded automatically upon the central recorder by means of pens operated by electro-magnets upon a paper record by embossing, puncturing or ink, also giving audible signal by means of bell, gong, buzzer, horn or whistle, and a visual indication consisting of a red light warning signal. The signal is also sounded, by the operation of an alarm box connected to the central recorder, to as many sub-recording stations as may be installed, or to any central station office or city fire department. When the proper water level has been restored a separate and distinctive signal is given, automatically recording upon the central recorder by means of pens operated by electro-magnets upon a paper record by embossing, puncturing or ink, also an audible signal by means of bell, gong, buzzer, horn or whistle and red light warning signal is automatically eliminated. Also, an audible signal is, by means of an alarm box connected to the central recorder, sounded to all sub-recording stations and red light warning signals upon sub-recording stations are automatically eliminated. Red light warning signals upon the central recorder are automatically eliminated upon the restoration of any particular water level, but remain visible upon all sub-recording stations until all water levels are restored to normal.

The operation in connection with temperature is preferably as follows: All gravity tanks, cisterns and reservoirs for sprinkler service in which water might freeze are equipped with a device which will give a separate and distinctive signal when temperature of the water falls below forty degrees Fahrenheit or rises above one hundred and sixty degrees Fahrenheit. These signals are recorded automatically upon the central recorder by means of pens operated by electro-magnets upon a paper record by embossing, puncturing or ink, also giving an audible signal by means of bell, gong, buzzer, horn or whistle, and a visual indication consisting of a red light warning signal. The signal is also sounded, by the operation of an alarm box connected to the central recorder, to as many sub-recording stations as may be installed, or to any central station office or city fire department. When the water has been restored to normal temperature a separate and distinctive signal is given, automatically recording upon the central recorder by means of pens operated by electro-magnets upon a paper record by embossing, puncturing or ink. Also, an audible signal by means of bell, gong, buzzer, horn or whistle and red light warning signal is automatically eliminated. Also an audible signal is by means of an alarm box connected with

the central recorder, sounded to all sub-recording stations and red light warning signals upon sub-recording stations are automatically eliminated. Red light warning signals 5 upon the central recorder are automatically eliminated upon the restoration of any particular temperature, but remain visible upon all sub-recording stations until all temperatures have been restored to normal.

10 The operation in connection with water flow is preferably as follows: At the base of each system riser contacts or switches are attached to each alarm valve to indicate the flow of water in the sprinkler system. In 15 case the water flow is equal or greater than ten gallons per minute, the alarm is automatically recorded upon the main or central recorder by means of pens operated by electro-magnets upon a paper record by embossing, puncturing or ink, giving a separate and distinctive alarm with visual indication designating the particular system riser through which water is flowing. By means 20 of an alarm box connected with the central recorder, these alarms are sounded upon all sub-recording stations and as many other points throughout the premises by means of bells, gongs, horns and whistles, or to any central station office or city fire department. 25 Red light warning signals upon the central recorder and sub-recording stations remain visible until alarm valve is again restored to normal.

30 The circuits controlling all devices are under constant electrical supervision with a permanent record, preferably showing an automatic test of the entire equipment every fifteen minutes, as a protection to and notification of accidental or malicious interruption to the circuits, batteries or attachments. The apparatus consists of a series of relays, 35 switches, electro-magnets, pens, signal lights, mechanical devices and paper record operated by a self-winding clock. All of the attachments or switches on gate valve, pressure devices, water levels and temperature, including water flow devices are connected to the central recorder by wires. Upon each central recorder there is installed one or 40 more alarm boxes which are operated by means of relays for the purpose of transmitting the alarms to all sub-recording stations, central station office or city fire department. All alarms or signals of whatever nature are 45 automatically recorded by means of pens operated by electro-magnets upon the paper record by embossing, puncturing or ink writing. All signals are easily legible and are accurately determined.

50 The full objects and advantages of my invention will appear in connection with the detailed description thereof and the novel features embodied in my inventive idea will be particularly pointed out in the claims.

55 In the accompanying drawings,—

Fig. 1 is a view of the wiring diagram of my system. Fig. 2 is a sectional elevational view of a recording device. Fig. 3 is a plan view of a timing mechanism. Fig. 4 is a fragmentary view of a record tape.

70

Referring to the accompanying drawings, the character 10 designates a source of electrical energy which is provided with a voltmeter 12 and an ammeter 14. A wire 16 leads from the electrical source so as to be in operative relation with a plurality of devices by means of similar connections and contrivances. Referring to one of these in detail, the wire 16 is connected through a resistance 18 and a wire 20 with a circuit controller 22 which is of the closed-circuit type and which opens to break the circuit when a device with which it is associated, such as a gate valve of an automatic sprinkler, assumes an abnormal condition. From 75 the controller 22 a wire 24 leads to the winding of an electro-magnet 26 connected by a wire 28 to the negative line 30 of the system. The electro-magnet is thus normally energized and the contact 32 is held up to the 80 contact 34, while the contact points of contact springs 36, 38, 40 and 42 are not at this time in the circuit. While the circuit 85 through the controller 22 remains closed the apparatus pertaining to any single unit remains idle with the exception of delinquent watchman mechanism and clock mechanism, which operates periodical tests, these two mechanisms being arranged for operation in 90 a manner which will be described later. 100 When the circuit through the controller 22 is broken the electro-magnet 26 is deenergized and the contacts 34, 32 and 36 are momentarily engaged, which causes current to flow through an electro-magnet 44 by way of the connection 46 and the wire 48, and from electro-magnet through the wire 50 to contacts 36, 32 and 34 and the connection 52 to the wire 28, and then to the connection 54 on the negative line 30. This action continues only while the armature of the electro-magnet 26 is in either its downward or upward movement and ceases when the armature has attained its extreme upward 105 or downward position, the upward movement, of course, occurring when the circuit through the controller 22 is again established. When the electro-magnet 44 is thus energized it will pull up the armature 56 to which is connected a pen or perforator 58, shown in Fig. 2, which makes a single mark or punch on a record tape 60 which is fed from a roll 62. It will be understood 110 that there is one of these pens for each of the electro-magnets 44 and that in practice the electro-magnets 44 are juxtaposed so as to bring the pens close together across the width of the tape. The result of this operation is that with every downward movement and also every upward movement of 115 120 125 130

the armature of one of the electro-magnets 26 a mark will be made on the record tape. When the electro-magnet 26 is deenergized the contact points of springs 32, 36 and also 5 of 38, 40 and 42 are engaged and remain in engagement until the electro-magnet 26 is again energized. While the contact points of springs 32 and 36 are engaged, current flows every two minutes through the wire 10 48 to the electro-magnet 44, and through the wire 50 to the contact springs 36 and 32, and through the wire 64 to the spring finger 66, to the notched wheel 68 and through the wire 70 to the negative line 30. 15 The wheel 68 has thirty notches around its circumference and is secured to a shaft 72 which is rotated once every hour by clockwork mechanism 74. The spring finger 66 is thus actuated every two minutes when 20 the device is not normal and for each actuation thereof causes a mark or punch to be made on the recorder tape, these marks merging into each other as indicated at 25 *a*, *c*, *d*, *e*, *f* and *g* in Fig. 4 on account of the slow movement of the record tape. When the electro-magnet 26 is deenergized the contact springs 38, 40 and 42 are engaged, thus allowing current flow from the positive line through the connection 76, through a wire 78, through the lamp 80 and wire 82 to contact 40 and contact 38, then to the negative line 30, and this also allows current to flow from the connection 84 through the relay 86 and wire 88 to the connection 90 and through the wire 92 to the contacts 42, 40, and 38, to the negative line 30. It will be understood that a plurality of electro-magnets 86 are provided for operating sub-stations. When 40 the relay 86 is energized the contact springs 94 and 96 are engaged, which allows current to flow from the connection 98 to the connections 100, 102 and 104 and through the lamp 106, the buzzer 108 and the transmitter coils 110 through the switch 112, the connections 114 and 116 to the contact 118, through the switch 120, through the wire 122 and the contact springs 94 and 96, through the wire 124 to the negative line 30. When 45 the transmitter coils 110 are energized the transmitter will start to run, which will make and break the circuit in accordance with the notches on the wheel 126 which operates contact springs 128 and makes and breaks the circuit at 130 to bells, relay, etc., the feed being from the contact 104 through the resistance 132 and the wire 134 to the negative line 30. In order to cut out the transmitter, the switch 120 is thrown to the 50 point 136, while to cut out the buzzer the switch 112 is thrown off the contact 116. When the switch 130 is thrown over to the point 136 it cuts out the transmitter, lights the lamp 136 and rings the buzzer 108. The 55 buzzer can be cut out by means of the switch

112, but the lamp will remain lighted until the switch 120 is returned to the point 118. In the diagram four relays 86 are shown which function alike, while an additional relay 138 operates like the others but has an additional device attached which is used for night watch service. Some of the electro-magnets, which correspond to the electro-magnets 26 and which are designated by the numeral 140, are capable of operating 70 through wires 142 connected to the bus-bar 144 for night watch service, or when a delinquent alarm device is desired. If the electro-magnets 140 have not been operated within a certain time, for example before 75 fifteen minutes after each hour, an hour wheel 144 secured on the shaft 72 and having a single projection 146 will make contact with a spring finger 148 which allows current to flow from the connection 150 through the electro-magnet coil 152, through the switch 154 to the spring finger 148 and through the wheel 144 to the wire 70 leading to the negative line 30. This causes the electro-magnet 152 to actuate its armature 156 and allows an arm 158 to drop and engage the contact 160 so that at fifteen minutes after the hour current flows from the connection 162 through the lamp 164, the buzzer 166 and the transmitter 168 to contacts 160 and 158, through the switch 170 to the spring finger 172 and through a quadrant 174 attached to a wheel 176 secured to the shaft 72, to the connection 178 and then to the negative line 30. The time 80 after the hour when it is desired that the delinquent signals shall operate may be varied by means of an adjusting screw 175, by means of which the position of the quadrant relatively to its wheel may be changed. 85 If the watchman is not delinquent and he operates the device connected to the bus-bar 144 before fifteen minutes after the hour, for instance, current will be supplied to the electro-magnet 180 through the operation of 90 the relay 138, which will allow current from the connection 150 to pass through the electro-magnet 180 to the contact 182, through the spring contacts 184 to the negative line 30, thus allowing the electro-magnet 180 to pull the arm 158 off the point 160, which will restore the delinquent alarm system to normal. These alarms can also 95 be restored by depressing the key 186, which allows current to pass from the connection 100 150 to the electro-magnet 180 and to the point 188 through the key 186 and to the negative line 30. The switch 154 when open serves to prevent the delinquent device from functioning. When the switch 105 170 is open the wheel 176 will not function. When the delinquent device operates a record such as indicated, by the marks *m*, *n*, *o* and *p* will be made on the record tape according to which particular watchman is de- 110 115 120 125 130

linquent. The wheel 190 is secured to and is insulated from the shaft 72 and has four projections 191 equally spaced so as to separate the contact fingers 192 and 194 every

5 fifteen minutes, which de-energizes the electro-magnet 196 to cause test marks *w* to be made on the record tape.

The operation and advantages of my invention will be understood from the foregoing description. The shaft 72, to which are secured the wheels 68, 144, 176 and 190, is rotated once every hour by the clock-work mechanism which also causes the record tape to be moved at a uniform rate past a 15 plurality of the marking elements, 58. The record tape in the embodiment shown is divided by transverse lines into spaces corresponding to hours and intervening fifteen-minute periods, and it is divided by longitudinal lines into spaces corresponding to the various items, in regard to which a record is

to be made. The wheel 190 operates to separate, momentarily, the contact fingers 192 and 194, every fifteen minutes and this causes

20 the electro-magnet 196 to be de-energized and energizes the particular one of the series of electromagnets 44 associated therewith, causing its armature to be attracted and register the test marks *w* which show that the mechanism is functioning properly. When

25 a device, associated with any one of the circuit-controllers 22 and corresponding electromagnets 26, assumes an abnormal condition, the electro-magnet 26 is deenergized and the electro-magnet 44 associated therewith is

30 momentarily energized, thus causing a mark to be made on the record tape by means of the armature 56 and attached pen at the exact time when the device assumes an abnormal condition. As long as the device re-

35 mains abnormal, the wheel 68 completes an electrical circuit every two minutes through the particular electro-magnet 44 and causes marks to be made successively on the record

40 tape, thereby producing records such as *a*, *c*, *d*, *e*, *f*, *g*,—the last mark in any record being made when the device becomes normal, since the armature of the electro-magnet 26 is then pulled upwardly and the electro-

45 magnet 44 is energized momentarily in the manner previously described. In Fig. 4, the record tape indicates the particular time during which the conditions in regard to

50 water-flow, gate-valve, pressure, water-level, temperature of water and fire door were abnormal. When any one of the devices be-

55 comes abnormal, the particular lamp 80 associated therewith is lighted and remains lighted until it is extinguished by the ener-

60 gization of the electro-magnet 26 at the time when the device becomes normal. Also when the device becomes abnormal, the proper relay 86 is energized, thereby light-

65 ing the co-related lamp 106 and actuating the corresponding buzzer and transmitter in

the manner previously described. The operation of the device in regard to delinquent watchmen has already been described in detail.

I claim—

1. An electrical signalling and recording system comprising a source of electricity, a circuit controller in the circuit of said source, and operable by a watchman, a shaft adapted to be rotated by clock-work mechanism, 70 an hour-wheel secured to said shaft, a fractional wheel secured to said shaft, means associated with said clockwork mechanism for feeding a record tape, means associated with said hour-wheel and with said fractional 75 wheel, whereby a record will be made on said tape when a watchman is delinquent in operating said controller, and means which automatically prevents operation of said last-mentioned means when the watchman is not 80 delinquent.

2. An electrical signaling and recording system comprising a source of electricity, a plurality of circuit controllers in the circuit of said source, means for feeding a record tape, means for marking said tape with a test record when the system is functioning properly, means operated by completion of electrical circuits whereby separate marks will be made on said tape when said circuit-controllers assume an abnormal condition 90 and return to normal condition, and means also operated by completion of electrical circuits for actuating signals at desired places during said abnormal period. 95

3. An electrical signalling and recording system comprising a source of electricity, a plurality of circuit-controllers in the circuit of said source, means for feeding a record tape, means for marking said tape with a test record when the system is functioning properly, means operated by completion of electrical circuits whereby separate marks will be made on said tape when said circuit-controllers assume an abnormal condition 100 and return to normal condition, means also operated by completion of electrical circuits for actuating signals at desired places during said abnormal periods, means whereby a record will be made on said tape and signals 105 will be operated when a watchman is delinquent in operating a circuit controller, and means which automatically prevents operation of said last-mentioned means when the watchman is not delinquent. 110

4. An electrical signalling and recording system comprising a source of electricity, a plurality of circuit controllers in the circuit of said source, a shaft adapted to be rotated by clock-work mechanism, a test wheel secured to said shaft, an interrupter wheel secured to said shaft, an hour-wheel secured to said shaft, a fractional wheel, secured to said shaft, means associated with said clock-work mechanism for feeding a 125 said clock-work mechanism for feeding a 130

record tape, means operated by said test wheel for marking said tape when said system is functioning properly, means operated by completion of electrical circuits whereby 5 separate marks will be made on said tape when said circuit controllers assume an abnormal condition and return to normal condition, connections with said interrupter wheel, whereby marks will be made during 10 such period, at intervals on said tape, means also operated by completion of circuits for actuating signals at desired places during said abnormal period, means associated with said hour wheel and with said fractional 15 wheel whereby a record will be made on said tape and signals will be operated when a watchman is delinquent in operating a circuit-controller, and means which automatically prevents operation of said last-mentioned 20 means when the watchman is not delinquent.

5. An electrical signalling and recording system comprising a source of electricity, a positive line leading from said source, a plurality of circuit-controllers connected to said line, a plurality of electro-magnets, the coils of which are connected to said circuit controllers, a negative line to which said electro-magnet coils are connected, a plurality of normally disengaged, contact members associated with each of said electro-magnets and which are engaged when said electro-magnets are de-energized, a shaft adapted to be rotated by clock-work mechanism, a test-wheel secured to said shaft, an interrupter wheel secured to said shaft, an hour-wheel secured to said shaft, a fractional wheel secured to said shaft, means associated with said clock-work mechanism for feeding a record tape, means operated by said test-wheel for marking said tape at regular intervals when said system is functioning properly, means operated by completion of electrical circuits through some of said contact members whereby separate marks will be made on said tape when said circuit controllers assume an abnormal condition and return to normal condition, connections with said interrupter wheel where- 40 by marks will be made during such period at regular intervals on said tape, means also operated by completion of circuits through said contact members for actuating signals at desired places, means associated with said

hour-wheel and with said fractional wheel 55 whereby a record will be made on said tape and signals will be operated when a watchman is delinquent in operating a circuit-controller and means which automatically prevents operation of said last-mentioned 60 means when a watchman is not delinquent.

6. An electrical signalling and recording system comprising a source of electricity, a positive line leading from said source, a plurality of resistances connected to said line, a plurality of circuit controllers connected to said resistances, a plurality of electro-magnets, the coils of which are connected to said circuit controllers, a negative line leading back to said source of electricity 70 and to which said electro-magnet coils are connected, a plurality of normally disengaged, contact members associated with each of said electro-magnets and which are engaged when said electro-magnets are de-energized, a shaft adapted to be rotated by clock-work mechanism, a test-wheel secured to said shaft, a notched wheel secured to said shaft, a one-tooth wheel secured to said shaft, a segment-carrying wheel secured to shaft, means associated with said clock-work mechanism for feeding a record tape, means operated by said test-wheel for marking said tape at regular intervals when said system is functioning properly, means operated by completion of electrical circuits through some of said contact members whereby separate marks are made on said tape when said circuit controllers assume an abnormal condition and return to normal 80 condition, connections with said notched wheel whereby marks are made on said tape at regular intervals between said separate marks, means also operated by completion of circuits through said contact members for actuating audible and visible signals at desired places, means associated with said one-tooth wheel and with said segment wheel whereby a record will be made on said tape and signals will be operated when a watchman is delinquent in operating a circuit controller, and means which automatically prevents operation of said last-mentioned means when the watchman is not delinquent. 90

In testimony whereof I hereunto affix my 95 signature.

JOHN M. DIEGEL.
